FUEL CONTAINER BASKET FOR USE IN AN OUT-DOOR GRILL AND OVEN COMBINATION

Edward J. Petrick, Park Ridge, Ill., assignor to Belford Manufacturing, Inc., a corporation of Illinois

Filed Apr. 4, 1961, Ser. No. 64,610

Term of patent 14 years

(Cl. D81—10)

Fig. 1.

Fig. 2.

Fig. 3.

*Fig. 4.**Fig. 5.*FIGURE 1 is a top plan view of a fuel container basket for use in an outdoor grill and oven combination showing my new design;

FIGURE 2 is a front elevational view thereof, the back being substantially the same in appearance but without a handle;

FIGURE 3 is a side elevational view thereof, the opposite side being substantially the same in appearance;

FIGURE 4 is a top perspective view thereof, taken from the front; and

FIGURE 5 is a side perspective view thereof, taken from the bottom.

I claim:

The ornamental design for a fuel container basket for use in an outdoor grill and oven combination, as shown and described.
